UNITED STATES PATENT OFFICE.

WARREN D. HUSE, OF LACONIA, N. H., ASSIGNOR TO ORISON TWOMBLEY, OF LAKE VILLAGE, N. H., AND THOMAS S. NOWELL, OF BOSTON, MASS.

KNITTING-MACHINE.

SPECIFICATION forming part of Letters Patent No. 331,402, dated December 1, 1885.

Application filed February 19, 1885. Serial No. 156,338. (No model.)

To all whom it may concern:

Be it known that I, WARREN D. HUSE, of Laconia, in the county of Belknap and State of New Hampshire, have invented certain new and useful Improvements in Circular-Knitting Machines, of which the following, taken in connection with the accompanying drawings, is a specification.

My invention relates to knitting-machines, and particularly to that class of knitting-machines in which a series of latch-needles are arranged so as to be moved endwise by a cam to form the stitches which constitute knitting; and it consists in certain novel features and arrangements of parts, whereby the lower ends of the needles may be moved laterally by swinging about a fixed fulcrum or axis at or near the hook end of said needles, so that the lugs secured to or formed upon said needles may be removed from the path of the cam whenever it is desired to throw the said needles out of action, all of which will readily be understood by reference to the description of the drawings, and to the claims to be herein-after given.

Of the drawings, Figure 1 represents a central vertical section of a portion of a circular-knitting machine embodying my invention. Fig. 2 represents a horizontal section of a portion of same, the cutting-plane being on line *x x* on Fig. 1. Fig. 3 represents a central vertical section of a portion of a circular-knitting machine embodying a modified form of my invention; and Fig. 4 represents a horizontal section of a portion of the same, the cutting-plane being on line *y y* on Fig. 3.

A is the needle-cylinder, firmly secured to the base-ring *B* in any suitable manner, and it has formed in its periphery a series of vertical grooves, *a a*, to receive and form guides for the needles *C C*. The needles *C C* are each provided with a lug, *b*, which projects outwardly into and is acted upon by the cam-path *c* of the cam-cylinder *D*, which is provided with the bevel gear-teeth *E*, to which rotary motion is imparted by a suitable bevel gear-wheel (not shown) in a well-known manner. The rotation of the cam-cylinder *D* imparts to the needles *C C* an endwise-reciprocating movement through the medium of the cam-path *c*, and the lugs *b b*, also, in a well-known

manner. The annular plate *F*, mounted upon the cylinder *A* by a driving fit, has a recess, *G*, in which the two segmental plates *H* and *H'*, placed one above the other, each provided at each end with the cam-like curve *i i'*, are adapted to be operated by means of the plates *I*, the eccentric *I'*, the two double-ended pawls *J J'*, &c., all as has been fully described in a pending application of mine, filed July 21, 1884, and numbered 138,349, and therefore need not be described more at length here. The grooves *a a* have their inner walls so inclined that said grooves are considerably deeper at their lower than at their upper ends, and the partitions between said grooves *a a* are cut away midway of their lengths, so as to form the annular groove *d*, in which the segmental plates *H H'* act against the needles *C C* when pressing said needles out of action. A spring, *K*, is placed in contact with the needle *C* in such a manner that it will always tend to keep the said needle in contact with the cam-cylinder *D* and the lug *b* in the cam-path *c*. The spring *K* may be placed within the groove *a* in a recess, *e*, made for that purpose, as shown in Figs. 1 and 2; or it may be placed between the cylinder *A* and the inner cylinder, *L*, which is provided with as many vertical grooves *f f* in its periphery as there are grooves *a a* in the periphery of the cylinder *A*, said grooves *f f* serving as guides to prevent the turning of the spring *K*, one end of which extends lengthwise of said groove, while the other end is bent horizontally, and, passing through the hole *g*, its extreme outer end presses against the inner side of the needle *C* with the tendency of keeping said needle in contact with the cam-ring *D*.

When it is desirous of throwing any of the needles *C* out of action, the segmental plates *H H'* are moved against them by mechanism substantially such as shown and described, or equivalents therefor, to such an extent that said needles are swung about a fulcrum, as at *h*, until the said needles come into contact with the inner walls of the grooves *a a* at the upper and lower portions thereof, the springs *K* being compressed to allow of such movement. It has been found by experiment to be of advantage to thus remove the needle from action without bending the needle, as no damage is

liable to be done thereto, as is the case when the needle is bent midway of its length, for in practice the needles were often broken at the bend in the lug by the repeated bending and 5 cramping of the needle-shank.

I am aware that knitting-machine needles have been thrown out of action by swinging them about a fulcrum at or near their hook ends, as in the Patent No. 140,800, of July 15, 10 1873, and in Patent No. 214,308, of April 15, 1879, and also that a spring has been used to throw a needle so thrown out of action into action again with its cam, as in English Patent No. 2,729 of 1871, and therefore I do not claim, 15 broadly, throwing a needle out of action with its cam by swinging it around a fulcrum at or near its hook end, or throwing it into action again by means of a spring; but

What I claim as new, and desire to secure 20 by Letters Patent of the United States, is—

1. The needle-cylinder A, provided with the grooves *a a*, made deeper at their lower than at their upper ends, the needles C C, provided with the lugs *b b*, the cam-cylinder D, provided 25 with the cam-path *c*, the segmental plates H H', adapted to be moved against said needles, so

as to throw them out of action, and the springs K K, adapted to press said needles into contact with said cam-path, substantially as described.

30

2. The needle-cylinder A, provided with the grooves *a a*, made deeper at their lower than at their upper ends, in combination with the needles C C, provided with the lugs *b b*, the cam-cylinder D, provided with the cam-path 35 *c*, the segmental cams H H', adapted to be moved against said needles, so as to throw them out of action, the cylinder L, provided with the longitudinal grooves *f* and secured to the interior of the cylinder A, and the 40 springs K, inserted between said cylinders A and L and extending through openings in said cylinder A into contact with the needles C, substantially as shown and described.

35

In testimony whereof I have signed my 45 name to this specification, in the presence of two subscribing witnesses, on this 2d day of January, A. D. 1885.

WARREN D. HUSE.
